UNITED STATES PATENT OFFICE.

CARL H. BISSELL, OF SYRACUSE, NEW YORK, ASSIGNOR TO CROUSE-HINDS COMPANY, OF SYRACUSE, NEW YORK, A CORPORATION OF NEW YORK.

ELECTRIC LANTERN.

Application filed January 9, 1923. Serial No. 611,581.

To all whom it may concern:

Be it known that I, CARL H. BISSELL, a citizen of the United States, and a resident of Syracuse, in the county of Onondaga 5 and State of New York, have invented a certain new and useful Electric Lantern, of which the following is a specification.

This invention has for its object the production of a portable electric lantern, which 10 is particularly simple in construction, economical in manufacture, and highly efficient and durable in use, and by which the lantern can be readily connected in a feed circuit and readily connected, if desired, in 15 multiple or in series with several other lanterns. The invention consists in the novel features, and in the combinations and constructions hereinafter set forth and claimed.

20 In describing this invention, reference is had to the accompanying drawings in which like characters designate corresponding parts in all the views.

Figure 1 is an elevation, partly in section 25 of my lantern.

Figure 2 is an inverted plan view thereof.

This lantern comprises generally, a body open at its lower end and closed at its top, and having light projecting openings 30 on opposite sides of its lower portion, a transverse support within the body above the upper ends of such openings, a lamp socket carried on the lower side of such support in position to carry a lamp in line 35 with such openings, means as plug receptacles in the body above the support by which temporary electric connection is made to a feed circuit and also by which temporary electric connection is made from the 40 feed circuit to another lantern or lamp, the wall of the body having plug receiving passages aligned with such plug receptacles, the body also having guards for the light projecting openings, and a detachable guard 45 at its lower edge, such guard preventing removal of the lamp from the socket.

The lower edge of the body is horizontal 50 so that the lantern will stand on a horizontal surface, and the detachable guard is arranged above the lower edge so as to permit the lantern to stand on its bottom edge. The body is also provided with a bail or hook by which it can be hung up.

1 is the body which is preferably cylindri- 55 cal in general form having a top wall 2 and

being open at its lower end. 3 are light projecting openings in diametrically opposite sides of its lower portion, the body being provided with upright radially extending reflecting flanges 4 at the outer sides of such 60 openings, and 5 is the upright guard or bar between the openings on each side. The flanges 4 are preferably struck from the body and when bent outwardly form the openings 3. The guards are upright bars 65 5 secured at their ends as by welding to the body at the margins bounding the upper and lower edges of the openings 3. These bars are so spaced relatively to the outer sides of the openings 3 as to prevent unscrewing and removal of the lamp from the 70 socket.

6 is the transverse support, it being preferably a horizontal partition in the body located above the upper ends of the openings 3.

7 is the lamp socket depending centrally from the lower side of the partition.

8 designates a plurality of electric connectors or plugs, or plug receptacles, there 80 being preferably three, two of which are located diametrically opposite each other, and the other midway between said two. The terminals of these plugs or receptacles are electrically connected to the terminals 85 of the lamp socket and to the terminals of each other in any well known manner, so that the lamp socket can be connected in the feed circuit and also if desired, other lanterns and lamps can be connected in 90 multiple with the lantern in the feed circuit. These plug receptacles are supported on the partition 6.

9 are plug receiving passages in the wall of the body in line with the receptacles 8. 95

10 is the removable guard across the lower end of the body and above its bottom edge, this guard being here shown as a U-shaped member or bolt passing through holes in the lower margin of the body and having 100 a tongue 11 also passing through a slot in the body and formed with an eye 12 for receiving the shackle of a padlock or other locking means. 13 is the bail or hook by means of which the lantern can 105 be hung up.

This lantern in addition to being simple and economical in construction, is particularly adapted for use in box cars, and in use is hung up between the doors with its open- 110

ings 3 toward the end of the car so that the light projected downwardly through the open bottom lights the middle of the car and that projected through the openings 5 lights the ends of the car.

Also a line may be led from one of the plug receptacles 8 to a lantern or lamp in a car on a parallel track, and further a line 10 may be led from another plug receptacle 8 to a lamp within the car to illuminate the desk of a clerk checking the loading or unloading of the cargo.

What I claim is:

1. A lantern comprising a body open at 15 its lower end and having a closed top and openings in diametrically opposite sides thereof, the body also having a horizontal partition above the upper ends of said openings, a lamp socket mounted on the lower 20 side of the partition in position to carry a lamp in line with said openings, plug receptacles mounted in the box above the partition and the walls of the body being formed with passages in line with the plugs, 25 substantially as and for the purpose described.

2. A lantern comprising a body open at 30 its lower end and having a closed top and openings in diametrically opposite sides thereof, the body also having a horizontal partition above the upper ends of said openings, a lamp socket mounted on the lower 35 side of the partition in position to carry a lamp in line with said openings, plug receptacles mounted in the box above the partition and the walls of the body being formed with passages on diametrically opposite sides thereof in line with diametrically 40 opposite plugs, substantially as and for the purpose specified.

3. A lantern comprising a body open at 45 its lower end and having a closed top and openings in diametrically opposite sides thereof, the body also having a horizontal partition above the upper ends of said openings, a lamp socket mounted on the lower 50 side of the partition in position to carry a lamp in line with said openings, and plug receptacles mounted in the box above the partition and arranged to face radially in a plurality of directions, and the body being formed with plug receiving passages alined 55 with said plug receptacles, substantially as and for the purpose set forth.

4. A lantern comprising a body open at 55 its lower end and having a closed top and opening in diametrically opposite sides thereof, the body also having a horizontal partition above the upper ends of said openings, a lamp socket mounted on the lower 60 side of the partition in position to carry a lamp in line with said openings, a plug receptacle mounted in the box above the partition, the wall of the box above the partition being formed with a plug receiving 65 passage alined with said plug receptacle, the body being provided with substantially radial outwardly extending flanges at the outer sides of said openings, substantially as and for the purpose described.

5. A lantern comprising a body open at 70 its lower end and having a closed top and opening in diametrically opposite sides thereof, the body also having a horizontal 75 partition above the upper ends of said openings, a lamp socket mounted on the lower side of the partition in position to carry a lamp in line with said openings, a plug receptacle mounted in the box above the partition, the wall of the box above the partition being formed with a plug receiving 80 passage alined with said plug receptacle, the body being provided with substantially radial outwardly extending flanges at the outer sides of said openings, and with an upright guard between the openings on each side for preventing removal of the lamp 85 from the body, substantially as and for the purpose specified.

6. A lantern comprising a body open at 90 its lower end and having a closed top and an opening in the side of the body, a lamp socket mounted in the upper portion of the body above such opening in position to 95 carry a lamp in line with the opening, the body being also provided with substantially radially and outwardly extending flanges at the sides of said opening and a detachable guard at the lower end of the body below 100 the lamp substantially as and for the purpose set forth.

In testimony whereof, I have hereunto signed my name, at Syracuse, in the county of Onondaga, and State of New York, this 105 9th day of December, 1922.

CARL H. BISSELL.
